[57] CLAIM

The ornamental design for a front panel for a data storage unit, as shown and described.

DESCRIPTION

FIG. 1 is a front perspective view of a front panel for a data storage unit showing my new design;

FIG. 2 is a front elevational view thereof, the undisclosed rear elevational view being unornamented;

FIG. 3 is a left side elevational view thereof;

FIG. 4 is a right side elevational view thereof;

FIG. 5 is a top plan view thereof; and,

FIG. 6 is a bottom plan view thereof.

The housing is shown in broken lines in the views for illustrative purposes only and forms no part of the claimed design.

FIG. 1

FIG. 2

FIG. 3

FIG. 4

FIG. 5

FIG. 6
